(57) **CLAIM**

We claim the ornamental design for a night light, as shown and described.

DESCRIPTION

FIG. 1 is a perspective view of a night light showing our new design;

FIG. 2 is a front view thereof;

FIG. 3 is a rear view thereof;

FIG. 4 is a side view thereof, the opposite side being a mirror image;

FIG. 5 is top view thereof; and,

FIG. 6 is a bottom view thereof.

The electrical plug shown in broken lines in FIGS. 1, 3, 4, 5, and 6 is for illustrative purposes only and is not part of the claimed design.

The environmental boundary defined by the broken lines in FIG. 3 is for illustrative purposes only and is not part of the claimed design.
